AIR CONDITIONING SYSTEM

William L. McGrath, St. Paul, Minn., assignor to
 Minneapolis-Honeywell Regulator Company,
 Minneapolis, Minn., a corporation of Delaware

Application July 16, 1937, Serial No. 154,026

28 Claims.

(Cl. 257—3)

My invention relates to air conditioning systems and is more particularly concerned with automatic controls therefor.

The primary object of my invention is to provide a novel automatic air conditioning system which is especially adapted to utilize an internal combustion engine driven refrigeration system for economically maintaining the temperature and humidity conditions of the interior of buildings or other structures within desired ranges of values.

One object of my invention is to provide an air conditioning system which employs an internal combustion engine as a driving means, such system being arranged for recovering the waste heat given off by such engine to provide reheat, and for also providing a source of heat for other purposes such, for instance, as for providing a supply of domestic hot water.

More specifically, it is an object of my invention to provide a closed system of this type with a simple and efficient arrangement for cooling the condenser of the refrigeration system and for recovering the heat dissipated by the internal combustion engine, thereby rendering the heat removed from the conditioned space and the waste heat from the engine available for providing a supply of domestic hot water and for providing reheat when necessary. With a system of this type the heat rendered available is often in excess of that needed for reheat or for heating domestic water, and consequently it is often necessary to dissipate a portion of the heat recovered in order to prevent overheating of the domestic water and to prevent delivery of hot cooling fluid to the condenser. It is therefore an object of my invention to provide an automatic control arrangement for preventing overheating of the domestic water and for controlling the dissipation of heat in a manner to maintain efficient condenser operation.

It is a further object of my invention to provide a novel control arrangement for maintaining the temperature and humidity of the air in the conditioned space within predetermined limits. In accordance with this phase of my invention, I provide for controlling the compressor output in a manner to increase said output upon increase in space temperature thereby decreasing the cooling coil temperature upon such increase in space temperature. For controlling the space relative humidity, I provide damper means controlling the air flow across the cooling coil, and further provide a reheat, the damper means and the reheat being controlled by a humidity

controller in a manner to first decrease the flow of air across the cooling coil when the humidity becomes excessive, and then to place the reheat in operation. By this arrangement the cooling dehumidification ratio of the cooling coil is varied to maintain both proper temperature conditions and proper humidity conditions, reheat being supplied whenever necessary and only when necessary for achieving this result.

Another object of my invention is the provision of an air conditioning system of the type employing a compression refrigeration system, with a modulating compressor output controller for maintaining a constant but adjustable refrigeration coil temperature, such controller being supplemented by a second controller responsive to the refrigeration load for varying the refrigeration coil temperature in a manner to maintain desired psychrometric conditions within the conditioned space, the control system being also adapted to automatically start the compressor when the pair of controllers demand a compressor output above a predetermined minimum value, said controllers acting also to place the compressor out of operation when the output demand is below such minimum value.

Further objects of my invention are the provision of an arrangement for limiting the action of the reheat to prevent overheating of the air by the reheat, and the provision of an arrangement for placing the internal combustion engine out of operation when the fan is stopped.

While my invention is more particularly concerned with air conditioning systems utilizing gas engines, certain novel features are of broader application.

Other objects of my invention will appear from the following description and the appended claims.

40 For a full disclosure of my invention, reference is made to the following detailed description and the accompanying drawings, in which:

Figure 1 is a diagrammatic illustration of a preferred form of my invention; and

45 Figure 2 is a similar view showing various modifications and additions to the system of Figure 1.

In the drawings, reference character 1 indicates an air conditioning chamber, this chamber having a return air inlet 2 which is connected by suitable duct means to the space to be conditioned 3. Said conditioning chamber is also provided with a fresh air inlet which is connected to the fresh air duct 4, suitable damper means (not shown) being provided for controlling the ad-

mittance of fresh air. The discharge end of the conditioning chamber is connected to the inlet of a fan 5, the discharge of said fan being connected by a discharge duct 6 to the conditioned space 3. The fan 5 may be driven by any suitable means and is herein shown as being driven by an electric motor 7 receiving its power from line wires 8 and 9. Within the conditioning chamber 1 is located a cooling coil 10, a partition 11 being disposed thereabove for providing a by-pass passage for the air around said coil. The flow of air over the coil and through the by-pass passage is controlled by means of a set of face dampers 12 and a set of by-pass dampers 13, these dampers being actuated in unison by means of an operating rod 14 which is secured to the operating arm 15 of an electric proportioning motor 16. The proportioning motor 16 is preferably of the type shown and described in Patent No. 1,989,972 issued on May 22, 1935, to Lewis L. Cunningham. This type of proportioning motor is adapted to be controlled by means of a potentiometer controller, and in accordance with my invention is controlled by means of the potentiometer type of space relative humidity controller generally indicated at 18. It will be understood that upon upward movement of the operating arm 15 of the proportioning motor 16 the face dampers 12 will be moved towards closed position and the by-pass dampers 13 will simultaneously be moved towards open position, thereby decreasing the flow of air across the cooling coil 10 and increasing the flow of air through the by-pass, and upon downward movement of the operating arm 15 the opposite action will take place. Also located within the conditioning chamber 1 is a reheater 19, this reheater being provided for heating the cooled air under certain conditions.

The cooling coil 10 is herein shown as being of the direct expansion type. For supplying liquid refrigerant to said cooling coil and for withdrawing the evaporated refrigerant therefrom, a compression type of condensing unit is provided, this condensing unit comprising a compressor 20 and a condenser 21. The discharge of the compressor is connected by a discharge line 22 to the refrigerant inlet of the condenser 21. The refrigerant outlet of the condenser 21 is connected to a conduit 23, this conduit conveying the liquid refrigerant to the expansion valve 24 which is connected to the inlet of the cooling coil 10. This expansion valve 24 may be of any desired type and is shown herein as being of the thermostatic type controlled in accordance with the outlet temperature of the cooling coil. It will be understood that a suitable receiver (not shown) may be interposed between the condenser and the expansion valve in accordance with established practice. The outlet of the cooling coil 10 is connected to an outlet conduit or suction line 25 to the suction side of the compressor 20. The operation of compression refrigeration systems of this type is well known in the art and therefore no detailed description of the operation of this system is necessary. It may be stated, however, that operation of the compressor 21 causes chilling of the cooling coil 10 and the temperature of the cooling coil 10 will vary in accordance with the speed of the compressor and in accordance with the quantity and temperature of the air passed over said cooling coil.

The compressor 20 is driven by means of an internal combustion engine 26. This internal combustion engine may be of any suitable type,

such for instance, as a gas engine, a Diesel engine, or a gasoline engine, and is herein shown as being provided with an inlet manifold 27 having connected thereto a fuel supply pipe 28, a throttle valve 29 being located in said fuel supply pipe for controlling the supply of fuel and hence the output of the engine. The internal combustion engine 26 is also provided with an exhaust manifold 30, a generator 31, and a starting motor 32. To the fly-wheel 33 of said engine is connected a drive shaft 34, this drive shaft having mounted thereon pulleys 35 and 36. The pulley 35 cooperates with suitable belts to drive the compressor 20, while the pulley 36 provides for driving a heat exchange fluid circulating pump 37.

In accordance with my invention, the operation of the internal combustion engine 26 is controlled in a manner to maintain a constant but adjustable cooling coil temperature, the cooling coil temperature maintained being varied in accordance with the temperature of the air within the conditioned space. This control is achieved by the use of a proportioning motor generally indicated at 40, a suction pressure controller 41, and a return air temperature controller 42.

Referring now to the proportioning motor 40, this motor comprises an operating shaft 43 for rotating the operating arm 44, which is connected by suitable linkage to the throttle valve 29. While I have shown the proportioning motor as positioning the throttle valve 29 directly, it will be understood that if desired the proportioning motor 40 may be arranged to adjust a speed regulator or governor for the engine which in turn operates said throttle valve. The operating shaft 43 is driven through a suitable gear train 45 by a reversible electric motor means comprising a pair of armatures 46 and 47 cooperating with respective field coils 48 and 49. The armature 46 and the field coil 48 comprise an induction motor for driving the operating shaft 43 in one direction, and the armature 47 and the field coil 49 comprise an induction motor for driving said operating shaft in the opposite direction. The energization of the field coils 48 and 49 is controlled by means of a suitable balancing relay 50, and by means of suitable limit switches 51 and 52. The limit switches 51 and 52 may be of any desired construction, and are shown herein as comprising normally engaged flexible contact blades which are adapted to be separated by means of an actuating member 53 which is mounted upon the operating shaft 43. It will be understood that when the operating shaft 43 rotates to either limit of rotation the operating member 53 will cause opening of the appropriate limit switch for deenergizing the operating motor to prevent injury to the apparatus.

Referring now to the balancing relay 50, this is shown as comprising a pair of serially connected relay coils 54 and 55. These relay coils are adapted to control through a suitable armature (not shown) a switch arm 56 which cooperates with a pair of contacts 57 and 58. When the relay coils 54 and 55 are equally energized the switch arm 56 will assume a position midway between the contacts 57 and 58. When, however, the relay coil 54 is energized more highly than coil 55, the switch arm 56 will be caused to engage the contact 57. Conversely, when the relay coil 55 is energized more highly than coil 54, the switch arm 56 will be brought into engagement with contact 58. The relative energization of the relay coils 54 and 55 is controlled by means

of the potentiometer type of controllers 41 and 42 and also by means of a balancing potentiometer 60, this potentiometer comprising a balancing arm 61 which is adapted to be rotated by rotation of the operating shaft 43, this balancing arm contacting with a balancing resistance 62. Upon clockwise rotation of the shaft 43, the balancing arm 61 will be shifted to the right across the balancing resistance 62, and upon opposite rotation of the shaft 43 movement of the balancing arm in the opposite direction will take place.

Referring now to the suction pressure controller 41, this controller comprises a bellows 64, this bellows being connected by a pipe 65 to the suction line 25 which leads from the outlet of the cooling coil 10 to the compressor 20. The bellows 64 is arranged to actuate a pivoted actuating arm 66, this arm having secured thereto a control arm 67 and a corrector arm 68. The control arm 67 is arranged to engage a control resistance 69 for forming a control potentiometer, and the corrector arm 68 is arranged to engage a corrector resistance 70. For urging the actuating arm 66 against the bellows, a tension spring 71 is provided, this spring being connected to the end of the actuating arm and to a suitable fixed element. It will be apparent that as the suction pressure increases, the bellows 64 will expand, thus tilting actuating arm 66 upwardly against the action of the spring 71, thereby causing counter-clockwise rotation of the arms 67 and 68 across their respective resistances. Upon a decrease in suction pressure, the opposite action will take place, namely, the bellows 64 will contract under the action of the spring 71, thereby causing rotation of the arms 67 and 68 in a clockwise direction.

The return air temperature controller 42 comprises a bellows 72, this bellows being connected by a capillary tube 73 to a control bulb 74 located in the return air passage. The bellows, tube, and bulb contain a suitable volatile fluid wherefore the vapor pressure within the bellows varies in accordance with changes in temperature at the control bulb 74. The bellows 72 actuates a pivoted bell-crank member having an actuating arm 75 and a control arm 76, said control arm co-operating with a control resistance 77 for forming a control potentiometer. A spring 78 is attached to the end of the actuating arm 75 for urging said arm against the bellows 72. Upon an increase in return air temperature, the vapor pressure of the volatile fill will increase, thereby causing expansion of the bellows 72 against the action of the spring 78, this causing upward movement of the actuating arm 75 and movement of the control arm 76 to the right across the resistance 77. Upon a fall in return air temperature, the vapor pressure of the volatile fill will decrease, this causing contraction of the bellows 72 by the action of the spring 78, which results in the control arm 76 being shifted towards the left across the resistance 77.

Reference character 80 indicates a step-down transformer having a high voltage primary 81 and a low voltage secondary 82. One side of the secondary 82 is connected by wire 83 to the left-hand end of the relay coil 54, and the other side of said secondary is connected by wire 84 to the right-hand end of relay coil 55. The relay coils 54 and 55 are therefore connected in series across the terminals of the transformer secondary 82. The left-hand end of resistance 77 and the right-hand end of resistance 69 are connected to the lower end of transformer secondary 82 by means

of wires 85, 86, 88 and 87, while the right-hand end of resistance 77 and the left-hand end of resistance 69 are connected to the upper terminal of said transformer secondary by means of wires 84, 88, 89 and 90. The lower end of the transformer secondary is also connected to the left end of balancing resistance 62 by wires 83 and 91, while the upper end of said secondary is connected to the right-hand end of the balancing resistance by wires 84 and 92. By the wiring arrangement just described, it will be apparent that the resistances 62, 69 and 77 are connected in parallel across the transformer secondary along with the relay coils 54 and 55 which are connected across said secondary in series. A flow of current will therefore take place through each of the resistances and through the relay coils 54 and 55. To the junction of the relay coils 54 and 55 is connected a wire 93, this wire being connected to the corrector resistance 70 of the controller 41 and to the control arm 76 of the temperature controller 42 through a rheostat 94. The wire 93 is also connected to a wire 95, which in turn is connected to the balancing arm 61 of the balancing potentiometer, a rheostat 96 being interposed in said wire. By the wiring just described the balancing arm 61, the control arm 67, and the control arm 76 are connected to the junction of the relay coils 54 and 55. This has the effect of causing each of the control arms and the balancing arm to divide its respective resistance into a first portion, which is parallel with the relay coil 54, and into a second portion which is in parallel with the relay coil 55. Therefore, movement of either of the control arms or the balancing arm across its resistance will change the value of resistance in parallel with the relay coils 54 and 55, thereby controlling the relative energizations of said coils.

With the control arms 67 and 76 in the position shown, that is, engaging the mid portions of their respective resistances, the amount of resistance in parallel with each of the relay coils is equal. For this position of the controllers, the operating shaft of the motor 43 has assumed a position in which the balancing arm 61 engages the mid portion of the balancing resistance 62, at which time the switch arm 56 will be disengaged from both contact 57 and contact 58. Assuming now that the return air temperature remains constant, if the suction pressure should increase, the control arm 67 of the controller 41 will be shifted in a counter-clockwise direction, this decreasing the portion of resistance 69 which is in parallel with relay coil 55 and increasing the portion of said resistance which is in parallel with relay coil 54, this causing an increase in current flow in coil 54 and a decrease in current flow in coil 55. This will result in switch arm 56 engaging the contact 57 and energizing the motor field 49 by a circuit as follows: transformer secondary 82, wire 84, wire 92, wire 98, switch arm 56, contact 57, wire 99, limit switch 52, wire 100, motor field 49, and wire 101 to the other side of secondary 82. Energization of the motor field 49 will cause the operating shaft 43 to be driven in a counter-clockwise direction, this causing opening of the throttle valve 29 to increase the speed of the engine. Simultaneously, with the opening movement of the throttle valve 29, the balancing arm 61 will be shifted to the left across the balancing resistance 62, this decreasing the portion of said resistance which is in parallel with the relay coil 54 and increasing the

portion of said resistance which is in parallel with the relay coil 55, thus tending to balance out the initial unbalancing effect of the controller 41. When the rotation of the shaft 43 results in such movement of the balancing arm 61 that the initial unbalancing effect of the controller 41 is balanced out, the switch arm 56 will disengage the contact 57 thereby deenergizing motor field 48, thus stopping the throttle valve 29 at this new position.

Upon a decrease in suction pressure the control arm 67 of the controller 41 will be shifted to the right across the control resistance 69, this decreasing the portion of said resistance which is in parallel with relay coil 54 and increasing the portion of said resistance which is in parallel with the relay coil 55. This will result in increasing the current flow in relay coil 55 and decreasing the current flow in relay coil 54, this causing switch arm 56 to engage the contact 58, and in a manner which will be apparent, will energize the motor field 48 for rotating the operating shaft 43 in a direction to close the throttle valve 29. As the throttle valve 29 is closing, the balancing arm 61 will be shifted to the right across the balancing resistance 62, thereby causing an increase in current flow in the relay coil 54 and a decrease in current flow in relay coil 55, this tending to balance out the initial unbalancing effect of the controller 41. When the movement of the throttle valve 29 is such that the balancing potentiometer rebalances the relay 50, the switch arm 56 will disengage the contact 58, thereby causing deenergization of the motor field 48, thus allowing the throttle valve 29 to remain in its new position. It will be apparent that for a given movement of the control arm 67 upon its control resistance, a corresponding movement of the balancing arm 61 on the balancing resistance 62 will be required for rebalancing the relay. Therefore, the movement of the throttle valve will be proportionate to the movement of the control arm 67 on its control resistance. The control arrangement just described, therefore, will act to position the throttle valve in accordance with changes in suction pressure, the throttle valve being opened for increasing the engine speed upon an increase in suction pressure, and being closed for decreasing the engine speed upon fall in suction pressure.

Assuming now that the suction pressure remains constant, if the return air temperature should increase, the control arm 76 of the controller 42 will be shifted to the right across the resistance 77, this decreasing the portion of said resistance which is in parallel with relay coil 55 and increasing the portion of said resistance which is in parallel with relay coil 54. This will cause the relay coil 54 to be more highly energized than coil 55 and will result in switch arm 56 engaging the contact 57 for driving the operating shaft 43 and the throttle valve 29 towards open position thus increasing the engine speed. In a manner which should now be apparent, when the movement of the throttle valve is such that the balancing potentiometer rebalances this unbalancing effect of the controller 42, the throttle valve 29 will be stopped in its new position. Upon a decrease in return air temperature, it will be apparent that the opposite action will take place, namely, that the throttle valve will be caused to be shifted towards closed position an amount proportionate to the decrease in temperature.

The purpose of the return air temperature controller 42 is to adjust the value of suction pressure which will be maintained by the suction pressure controller 41 in accordance with changes in return air temperature. As the suction pressure controller 41, therefore, is to maintain varying values of suction pressure, it is necessary to make the operating range of said controller less than its total range. In other words, it is necessary to arrange said controller so that a movement of the control arm 67 through but part of its range will cause the throttle valve to be shifted from full open to full closed position and vice versa. For this purpose, the rheostat 96 is inserted between the balancing arm 61 and the junction of the relay coils 54 and 55. This rheostat has the function of decreasing the current flow through the balancing arm 61 and therefore decreases the sensitivity or rebalancing effect of the balancing potentiometer. By the use of this rheostat, a small movement of the control arm 67 on the resistance 69 may be made to cause such an unbalancing of the relay coils that a relatively large movement of the balancing arm is required for rebalancing. By properly adjusting the rheostat 96, a predetermined change in value of suction pressure may cause a movement of the throttle valve 29 from one extreme to the other. The rheostat 96 therefore makes the operating range of the controller 41 less than its total range of operation.

As above stated, the controller 42 acts to adjust the value of suction pressure maintained by the controller 41. This action is accomplished as follows. Assuming a constant suction pressure and a rise in return air temperature, the controller 42 will be shifted to cause opening of the throttle valve 29 an amount determined by the degree of temperature rise. This opening movement of the throttle valve 29 will increase the fuel supply to the engine, thereby increasing its speed. The resulting increase of the compressor speed will result in the suction pressure beginning to fall. In response to this decrease in suction pressure, the controller 41 will begin shifting the throttle valve 29 towards closed position thus decreasing the speed of the engine, and when the suction pressure falls to such an extent that the resulting decrease in operation of the compressor stops further fall in suction pressure, the suction pressure will be maintained constant at this point. An increase in space temperature, therefore, will have the effect of causing the controller 41 to maintain a lower suction pressure. A decrease in space temperature will have the opposite effect, that is, the controller 42 will act to close the throttle valve 29 thus decreasing the compressor speed, which results in the suction pressure beginning to rise. In response to this rise in suction pressure, the controller 41 will begin moving the throttle valve towards open position to increase the speed of the compressor, and when the suction pressure has increased to such an extent that the resulting increase in operation of the compressor prevents further suction pressure increase, the suction pressure will remain constant at this point. Upon falling space temperature, therefore, the suction pressure controller will be adjusted to maintain a higher value of suction pressure. It will be noted that the rheostat 94 is interposed between the control arm 76 of controller 42 and the junction of the relay coils 54 and 55. The purpose of this rheostat is to provide an adjustment for varying the effect of changes in temperature upon the suction pres-

sure. It will be apparent that by increasing the resistance of the rheostat the effect of the controller 42 will be diminished and by decreasing said resistance the effect will be increased. Thus by properly adjusting this rheostat, any desired change in suction pressure for a given change in space temperature may be obtained. The purpose of the corrector arm 68 and the corrector resistance 70 on the controller 42 is for compensating or correcting the operation of the controller 41 when the value of suction pressure maintained is near either limit of the range of said controller.

From the foregoing description, it should be seen that the controllers 41 and 42 conjointly control the throttle valve 29 to vary the speed of the compressor hence the coil temperature in a manner to meet the prevailing refrigeration load. In accordance with my invention, I also provide an arrangement whereby these controllers act to cause starting of the internal combustion engine whenever the refrigeration load is sufficient to justify operation of said engine and to cause stopping of said engine when the refrigeration load is so light that inefficient operation of the engine would result. For obtaining this result, an auxiliary switch generally indicated as 102 is mounted to be actuated by the operating shaft 43 of the proportioning motor 40. Switch 102 comprises a bell-crank member having an actuating arm 103 and a switch carrying arm carrying a mercury switch 104. Mounted upon the operating shaft 43 is a switch operating member 105, this operating member being arranged to engage the actuating arm 103 and rotate the bell-crank lever so that mercury switch 104 is tilted to open position when the throttle valve 29 is moved to a predetermined closed position. When the throttle valve is opened to a predetermined position, however, the operating member 105 will be rotated so as to permit a spring 106 to tilt the mercury switch 104 to closed position. The mercury switch 104 is connected to control a suitable automatic starting and stopping control mechanism for the engine 26. For purposes of illustration, I have shown this control mechanism as being of the type illustrated in the Loehr Patent No. 1,773,913 issued August 26, 1930. It will be noted that one terminal of the mercury switch 104 is connected to a storage battery 107 by a wire 108, the other terminal of the storage battery being grounded. The other terminal of the mercury switch 104 is connected by wires 109 and 109a to an ignition coil 110, and by the wire 109 to a starting relay 111. By this arrangement, when the mercury switch 104 is tilted to closed position due to the throttle valve 29 being opened to a predetermined position, the ignition circuit for the engine will be completed and simultaneously the starting relay will cause operation of the starting motor, thereby starting the engine. When the throttle valve is closed to such a position as to indicate that the engine should be stopped, the mercury switch 104 will be tilted to open position, this deenergizing the ignition and the starting mechanism so that the engine stops. It will be noted that mercury switch 104 is of the bent type. This type of switch is desirable here as it has a wide angle of operation and thus will prevent any possibility of short-cycling of the apparatus. While for illustrative purposes I have shown the engine controlling switch as being of the mercury type, it will be understood that any suitable form of switch may be employed.

When the internal combustion engine is being started, it will be apparent that no appreciable load can be placed thereon. It is, therefore, necessary to provide an unloading device for removing the load from the engine during the starting operation. For this purpose, I have provided a by-pass 112 between the compressor discharge line 22 and the suction line 25, this by-pass having located therein an electrically operated valve 113. This valve 113 is shown as being of the type which opens when deenergized and which closes when energized. This valve is controlled by means of a controller 114 which is responsive to the pressure within the intake manifold 27 and comprises a bellows for actuating a mercury switch 115. The controller 114 is so arranged that when atmospheric pressure exists within the intake manifold 27, the mercury switch 115 will be tilted to closed position, this resulting in opening of the valve 113. It will be apparent that when the engine is out of operation the intake manifold pressure will be substantially atmospheric, and this will result in the valve 113 being held open. Thus, while the engine is being started, the compressor 20 instead of compressing the refrigerant will merely force refrigerant from the discharge line into the suction line. The compressor will, therefore, be unloaded during the starting operation of the engine. After the engine starts, however, a vacuum will be developed within the intake manifold 27, this causing contraction of the bellows to tilt the mercury switch 115 to closed position as shown, whereby the valve 113 is caused to close thus preventing further passage of refrigerant through the by-pass 112. By this arrangement, therefore, the compressor is unloaded during the starting period of the engine and the load is automatically thrown on the compressor after the engine is in operation.

My invention also includes a novel arrangement for recovering the waste heat of the internal combustion engine and for recovering the heat given off by the condenser, this heat being made available for providing a source of heat supply which may be used for heating domestic water or for reheat. This heat recovery system will now be described in detail. Reference character 116 indicates a source of cooled water or other heat exchange fluid which may take the form of an evaporative cooler, a spray pond, or any other type of cooler. To the outlet of cooler 116 is connected a pipe 117 which in turn is connected to a pipe 118 leading to the inlet of the water circulating pump 31. The discharge of pump 31 is connected by a pipe 119 to the cooling water inlet of the condenser 21. The cooling water outlet of the condenser 21 is connected by means of a pipe 120 to the inlet of the water jacket of the engine 26. The water jacket outlet of engine 26 is connected to a pipe 121 which leads to the coil 122 of an exhaust gas heat exchanger 123, this heat exchanger being connected to the exhaust manifold 30 by means of an exhaust pipe 124. The outlet of the heating coil 122 is connected to a pipe 125, this pipe leading to the inlet of a three-way valve 126. This three-way valve 126 may be of any desired type and is herein shown for illustrative purposes as being of the balanced piston type including a pair of pistons for selective covering or uncovering a pair of outlet ports. One outlet port of the three-way valve is connected by a pipe 127 to the heating coil 123 may be located in a storage tank as 129. The outlet of coil 128

is connected by a pipe 130 to the inlet of a second three-way valve 131. The other outlet of the three-way valve 126 is connected by a pipe 132 to the pipe 130. The three-way valve 126 therefore acts to control the flow of the heated fluid through the heating coil 128 and through the by-pass 132 around said heating coil.

From the arrangement described thus far, it will be seen that cooling fluid is first passed through the condenser for condensing the refrigerant, and that this fluid is heated by the heat removed from the refrigerant during the condensing action. The heated fluid after leaving the condenser is further heated by passage through the jacket of the internal combustion engine and is still further heated by passage in heat exchange relationship with the exhaust gases from the engine. The fluid leaving the exhaust gas heat exchanger 123 is therefore highly heated, and this fluid is passed either through the heating coil 128 of the storage tank or heat accumulator 129, or through the by-pass 132 around such coil, or partly through the heating coil and through the by-pass, depending upon the position of the three-way valve. The position of the three-way valve is controlled in accordance with the temperature within the tank 129 by means of a temperature controller 135 and a proportioning motor 136 which is arranged to actuate said valve. The controller 135 is similar to the temperature controller 42 which has previously been described and therefore is not described in detail. It will be noted, however, that the control bulb of this controller is located within the storage tank 129 so that the position of the potentiometer slider on the resistance varies in accordance with the storage tank temperature. The controller 135 is connected to the proportioning motor 136 in such manner that upon an increase in temperature of the storage tank, the operating arm 137 of the proportioning motor 136 will be rotated counter-clockwise, this having the effect of reducing the flow of heated fluid through the heating coil 128 and increasing the flow of heated water through the by-pass. Thus, as the tank temperature increases, the supply of heated fluid to the heating coil is reduced. Upon a fall in temperature of the tank, it will be apparent that the opposite action will take place, namely, the three-way valve 126 will be positioned so as to increase the supply of heating fluid to the coil 128. In this manner the supply of heating fluid to the coil 128 is controlled for maintaining the tank temperature constant, thereby preventing overheating of the water or other fluid in said tank.

As mentioned before, the fluid which passes through the coil 128 and the by-pass 132 is re-united in the pipe 130 and flows to the inlet of the three-way valve 131. This three-way valve has one outlet which is connected by a pipe 138 to the inlet of the cooler 116, the other outlet of said three-way valve being connected to the pipe 118 which in effect forms a by-pass around the cooler 116. The three-way valve 131 therefore acts to control the quantity of fluid which is passed through the cooler 116. This three-way valve is controlled in a manner to prevent the temperature of the cooling fluid being supplied to the condenser from exceeding a predetermined value, this being achieved by the use of a proportioning motor 140 and a temperature controller 141. The temperature controller 141 is similar to the controllers 42 and 135 and the control bulb of the controller 141 is located so

as to be responsive to the temperature of the cooling fluid passing to the condenser. For convenience in disclosure, I have shown this control bulb as located at the inlet of the pump.

- 5 It will be understood, however, that if desired this bulb may be placed at the pump outlet. The controller 141 is connected to the proportioning motor 140 in such a manner that upon an increase in temperature of the cooling fluid flowing to the condenser, the motor 141 will position the three-way valve for increasing the flow of cooling fluid through the cooler 116 and decreasing the flow through the by-pass, thereby counteracting the tendency of the temperature to increase. Conversely, if the temperature of the cooling fluid for the condenser falls, the three-way valve will be positioned to decrease the portion of the fluid flowing through the cooler and to increase the portion flowing through the by-pass. By this arrangement, it will be apparent that no more cooling fluid is passed through the cooler 116 than is necessary to prevent the temperature of such cooling fluid from exceeding a predetermined value, such as 20 100° F. The cost of heat dissipation is thereby held at a minimum and at the same time all of the heat which can be utilized for reheating or for domestic water or other uses is retained by the system.
- 30 It will be understood that the heated liquid in tank 129 may be used for any desired purpose, including the provision of heating fluid for the re heater 19. For providing the re heater 19 with heating fluid, a pipe 145 is connected to the upper end of the tank 129, this pipe leading to the inlet of re heater 19. The outlet of re heater 19 is connected by means of pipe 146 to the intake of a circulating pump 147, this pump being driven by an electric motor 148 and discharging into the inlet of a three-way valve 149. One outlet of the three-way valve is connected to the bottom of the tank 129 by means of a pipe 150 and the other outlet of said valve is connected by a pipe 151 to the pipe 145, this pipe 40 45 50 55 60 65 70 75 thereby forming a by-pass for the flow of water around the tank 129. The three-way valve 149 is positioned by means of a proportioning motor 152, this proportioning motor being also arranged to actuate a switch 153 which is in the circuit of the pump motor 148, said switch being arranged to stop the pump whenever the three-way valve is positioned so that the flow of water through pipe 150 is shut off. It should be apparent that adjustment of the three-way valve 149 will change the proportions of the hot liquid from the tank 129 and the recirculated liquid passing through the by-pass which are passed to the re heater 19, and will therefore vary the temperature of the heating medium supplied to said re heater.

The proportioning motor 152 and therefore the temperature of the heating medium supplied to the re heater is controlled by the humidity controller 18 which also controls the face and by-pass dampers 12 and 13. Referring now to the humidity controller 18, this controller comprises a humidity responsive device comprising a plurality of strands 155 of hair or other moisture responsive material, these strands being secured at their upper and lower ends by clamping members 156 and 157, the lower clamping member 157 being secured to a suitable fixed element. The upper clamping member 156 is connected to the actuating arm 158 of a bell-

crank lever having a control arm 159 cooperating with a control resistance 160 to form a control potentiometer. A tension spring 161 is attached to the end of control arm 158 for urging said arm upwardly to stress the strands 155. The control arm 155 is also arranged to actuate a second control arm 162 by any suitable means, this control arm 162 cooperating with a control resistance 163 for forming a second control potentiometer. The control potentiometer formed of arm 159 and resistance 160 is connected to the damper actuating motor 15, and the control potentiometer formed of arm 162 and resistance 163 is connected to the proportioning motor 152 for the reheat control valve. Upon an increase in humidity, the strands 155 will increase in length, this permitting the spring 161 to cause rotation of the arms 159 and 162 in a clockwise direction, while upon a decrease in humidity the strands 155 will decrease in length, thus causing rotation of the arms 159 and 162 in the opposite direction.

It will be noted that the resistances 160 and 163 each occupy but one-half of the range of movement of their respective control arms, contact segments being provided for said control arms when they are positioned so as to disengage their respective resistances. The purpose of this arrangement is to provide a sequential control for the dampers and the reheat control valve. With the control arms in the positions shown, it will be noted that the control arm 159 is engaging the midportion of the resistance 160 and for this position of said control arm, the proportioning motor 16 has assumed a position in which the face and by-pass dampers 12 and 13 are each half open. At this time, the control arm 162 is entirely off the control resistance 163 and is engaging the contact segment which is connected to the left-hand end thereof. For this position of the control arm 162, the proportioning motor 152 has assumed an extreme position in which all flow of heated fluid from the storage tank 129 is stopped and in which also the mercury switch 153 is tilted to open position for placing the pump 147 out of operation. If the space relative humidity increases, the control arms 159 and 162 will be rotated in a clockwise direction. The movement of control arm 159 on the resistance 160 will cause the proportioning motor 16 to correspondingly close the face dampers 12 and open the by-pass dampers 13. The corresponding movement of the control arm 162 will have no effect upon the proportioning motor 152, as said control arm will still be engaging the contact segment. When the relative humidity increases to such an extent that both arms 159 and 162 are upright, it will be apparent that the face dampers 12 will be completely closed and the by-pass dampers 13 will be wide open and that also the three-way valve motor 152 will be in the position shown, in which the pump 147 is out of operation. If now should the relative humidity increase further, the face dampers will remain closed and the by-pass dampers open, due to the arm 159 then engaging the contact segment connected to the right end of resistance 160. Now, however, the control arm 162 will be riding the control resistance 163, this causing the positioning of the three-way valve 149 to supply heating fluid to the reheat, the mercury switch 153 being tilted to cause operation of the pump 147. Upon still further

increase in relative humidity, the three-way valve will be positioned to increase the portion of heated fluid supplied to the reheat 19 thereby increasing the heating effect of said reheat. From the foregoing description, it should be apparent that when the relative humidity is low the reheat will be out of operation and the by-pass dampers closed and the face dampers open. As the relative humidity increases, the dampers will gradually be positioned so as to cause closing of the face dampers and opening of the by-pass dampers, the reheat being still out of operation. When, however, the by-pass dampers are wide open and the relative humidity continues to increase, the reheat will be placed into operation and the heating effect thereof will be increased upon further increase in relative humidity.

Operation

With the parts in the position shown, the space temperature is at an intermediate value as indicated by the control arm 76 of the space temperature controller engaging the center of its cooperating resistance, and for this value of space temperature the suction pressure controller is maintaining an intermediate value of suction pressure as indicated by the control arm 67 of the suction pressure controller engaging the center of its cooperating resistance. For this position the throttle valve 29 is at half open position and the mercury switch 104 is tilted to closed position. The engine 26 is therefore in operation for maintaining the desired temperature of the cooling coil 10. Also the space relative humidity is slightly excessive as indicated by the control arm 159 engaging the midportion of the control resistance 160, and for this value of humidity the face and by-pass dampers are positioned so that part of the air flows across the cooling coil and an equal part is by-passed therearound.

If now should the space temperature increase, due, for instance, to increasing outdoor temperature, two actions for increasing the speed of the compressor will occur. Due to the higher temperature of the air flowing across the cooling coil 10, an increased amount of refrigerant will be evaporated, this causing a rise in suction pressure. In response to this rise in suction pressure, the pressure controller 41 will act on the throttle valve motor 40 for opening said throttle valve somewhat to cause an increase in engine speed. Also, the return air temperature controller will act in response to the increase in temperature to demand a lower cooling coil temperature, this additionally affecting the throttle valve motor 40 for increasing the engine speed. Due to this lowering in cooling coil temperature caused by the return air temperature controller 42, an increased amount of heat will be absorbed by the cooling coil 10, this acting to stop the rise in temperature within the conditioned space. If the temperature should decrease within the conditioned space due to decrease in the cooling load, the temperature controller 42 will act to adjust the suction pressure controller 41 in a manner to maintain a higher coil temperature. Due to this adjustment, and also due to the fact that less refrigerant will be evaporated by the cooler air, which tends to cause a reduction in suction pressure, the suction pressure controller 41 will act to cause closing of the throttle valve 29, which in turn results in slowing down of the engine. Due to

the higher coil temperature now maintained, the cooling effect of the cooling coil 10 will be reduced, thereby preventing further fall in temperature of the air within the conditioned space.

It will be apparent that as the cooling load decreases, the control system described will cause progressive closing of the valve 29, and that when the throttle valve is closed to such an extent that mercury switch 104 is tilted to open position, the engine 26 will stop. Also, assuming the engine to be stopped, as the demand for conditioning increases, the throttle valve 29 will be opened and when it is opened sufficiently to cause closing of mercury switch 104, the engine will be automatically started, the compressor unloading valve 113 being opened during the starting period for the engine and being automatically closed after the engine has started.

Assuming again that the system is in operation, if the relative humidity should increase, the humidity controller 18 will cause closing movement of the face dampers 12 and opening movement of the by-pass dampers 13. This will result in decreasing the rate of air flow across the cooling coil 10, which in turn will result in decreasing the cooling effect of said coil. This decrease in the cooling action of the coil 10 will eventually result in a rising space temperature, and in response to this rising temperature, the temperature controller 42 will adjust the controller 41 for maintaining a lower suction pressure. This will result in lowering the temperature of the cooling coil 10 thereby increasing the dehumidifying effect of said coil to counteract the increase in humidity. If the relative humidity should continue to increase, the face dampers 12 will be further closed and the by-pass dampers 13 further opened, thus decreasing the cooling effect of the coil 10 even further for causing a higher space temperature, which in turn will result in the space temperature controller 42 demanding an even lower coil temperature for counteracting such increase in relative humidity. After the by-pass dampers 13 are wide open and the face dampers 12 are moved to their minimum position, if the relative humidity should continue to increase, the reheater 19 will be brought into operation for actually heating the air supplied to the space for causing such a space temperature rise as will result in the space temperature controller demanding lower coil temperatures. Upon falling humidity, it will be apparent that the opposite action will take place, namely, the reheater 19 will be placed out of operation and then the face dampers will be gradually opened and the by-pass dampers gradually closed, this resulting in the reverse effect upon the temperature controller 42 for raising the coil temperature to decrease the dehumidifying effect thereof. By this sequential damper and reheat control, it will be apparent that addition of heat to the air is avoided at all times except when absolutely necessary for lowering the relative humidity to the desired value.

It should be noted that the control by the three-way valves 126 and 131 will automatically prevent the temperature of the liquid in the tank 129 from becoming excessive and will also act to dissipate just enough heat in the cooler 116 as to prevent the temperature of the cooling water supplied to the condenser from becoming too high. Thus if the demand for domestic hot water or other heated fluid is such that all of the heat recovered from the condenser and the in-

ternal combustion engine is utilized, the temperature within the tank 129 will fall to such an extent that the temperature controller 145 causes all of the heated fluid to be supplied to the heating coil 128. However, as the demand for heated fluid decreases, the temperature in tank 129 will increase, this resulting in the temperature controller 135 causing movement of the three-way valve 126 for decreasing the flow of fluid through the coil 128. This will result in the temperature of the mixture of water from the by-pass and the coil 128 increasing, which in turn will cause the temperature of the mixture of water flowing to the condenser to increase. In response to this increase in cooling water temperature, the temperature controller 141 will position the valve 131 in a manner to cause flow of a sufficient part of the water through the cooler 116 as to prevent the temperature of the cooling water supplied to the condenser from becoming excessive.

Referring now to Figure 2, this figure shows exactly the same air conditioning apparatus as shown in Figure 1, and hence this apparatus is not described here in detail. This figure shows several modifications which may be made in the control apparatus, which will now be described.

In Figure 1, it will be noted that the solenoid unloading valve 113 is controlled by means of a controller responsive to the manifold pressure of the engine. In Figure 2, I have shown a solenoid valve 113a which corresponds to the valve 113 of Figure 1. This valve 113a, however, is of the type which opens when energized and which closes when deenergized. This valve, instead of being controlled by an engine manifold pressure controller as in Figure 1, is energized simultaneously with the starting motor 32 of the internal combustion engine 26. For this purpose the solenoid valve 113a is connected by a wire 200 to the wire 201 which leads from the relay 111 to the starting motor 32. By this arrangement, when the starting motor 32 is energized by the starting relay 111, the valve 113a will be energized thereby causing it to open. Therefore, when the internal combustion engine 26 is being started, the valve 113a is opened, which permits bypassing of refrigerant from the discharge of the compressor to the suction side, thereby unloading the compressor to permit starting of the engine. When the engine starts, the relay 111 will deenergize the starting motor, and will simultaneously deenergize the valve 113a, this causing said valve to close for placing the refrigeration system in operation.

As in the case of Figure 1, the throttle valve 29 of the engine is actuated by a proportioning motor 40 under the control of a return duct temperature controller 42. In this figure, however, the internal wiring of the motor 40 has not been illustrated, and for convenience, the mercury switch 104 is illustrated as being actuated by the actuating arm 44 of the motor 40.

If desired, the control system may be arranged to place the entire air conditioning system out of operation whenever the fan motor 5 is deenergized. For this purpose, I have shown a relay 202. This relay consists of a relay coil 203 which actuates through a suitable armature (not shown) a switch arm 204 which cooperates with contact 205. The switch arm 204 and contact 205 are interposed in the wire 109 which leads from the mercury switch 104 to the starting relay 111. The relay coil 203 is connected by wires 8b and 9b to the line wires 8a and 9a to which are connected the wires 8 and 9 leading to the

fan motor 5. When the line switch to line wires 8a and 9a is closed, the fan motor 5 will be energized for causing a flow of air through the conditioning chamber. Also at this time, the relay coil 203 will be energized which causes engagement of switch arm 204 with contact 205. This completes the circuit from mercury switch 104 to the starting relay 111 and thereby places the mercury switch 104 in control of the engine 20 for starting and stopping the same. When the line switch for the fan is opened, however, the relay coil 203 will be deenergized, which causes switch arm 204 to disengage contact 205 thereby breaking the circuit from mercury switch 104 to the starting relay. This will prevent the starting relay 111 from starting the engine and will also deenergize the ignition coil 110. This arrangement therefore prevents operation of the engine 26 whenever the fan is not operating.

My invention also contemplates the provision of an arrangement for preventing the reheat 19 from overheating the space. It will be apparent that when the reheat is controlled by means of a humidity controller, if the humidity becomes excessive, the humidity controller may cause the reheat to deliver heat to the space in such an amount as to actually heat up the space. In order to prevent this action, I have provided a reheat limit controller generally designated at 210. This controller may comprise a control arm 211 which is pivoted at 212 and which cooperates with a resistance 213 to form a control potentiometer. Control arm 211 is actuated by a pair of opposed bellows 214 and 215 which operate said control arm through a stem 216. The bellows 214 is connected by a capillary tube to a control bulb 217 located within the return duct. The bellows 215 is connected by a capillary tube 218 to a control bulb 219 located within the discharge duct 6. It will be understood that each bulb contains a suitable volatile fluid for causing varying pressures to be exerted upon the respective bellows upon changes in temperature at the control bulbs. The control arm 211 is biased by means of a spring 220, this spring tending to cause said control arm to move to the left across the control resistance 213. By this arrangement, it will be apparent that when the return and discharge temperatures at the control bulbs are equal, the pressures within bellows 214 and 215 will be equal, thereby causing the spring 220 to urge control arm 211 towards the left end of resistance 213. When the temperature of the discharge air is lower than the temperature of the return air, however, a greater pressure will be exerted within bellows 214 than within the bellows 215, this urging the control arm 211 against the action of the spring 220 towards the right-hand end of control resistance 213. It will be apparent that when the discharge air temperature is a predetermined amount below the return air temperature as determined by the tension of spring 220, the control arm 211 will engage the extreme right-hand end of control resistance 213. As this differential in temperature decreases, however, the control arm 211 will be shifted towards the left across resistance 213.

The limit controller 210 is connected into the control circuit of the reheat proportioning motor 152 in a manner to place the humidity controller 18 in full control of said proportioning motor whenever the discharge air temperature is a predetermined amount lower than the return air temperature. When this differential in temperature decreases below the predetermined value,

however, the limit controller 210 will act to position the proportioning motor 152 independently of the humidity controller 18 to cause the heating effect of reheat 19 to be reduced. This arrangement will now be described.

The proportioning motor 152 is of the same type as the proportioning motor 40 which has been described in detail in Figure 1, and includes a balancing relay of the type diagrammatically illustrated at 50 in Figure 1. This relay 50, it will be noted, consists of relay coils 54 and 55 which are connected together, and a wire leading from their junction point. This wire in the art is termed the "red" wire. Also, the other ends of the relay coils are connected to control wires which are termed the "white" and "blue" wires. From the description of Figure 1, it should be apparent that the position assumed by the proportioning motor will be dependent upon the resistance connected between the red and white wires and between the red and blue wires. Thus, when the resistance between the red and white wires is equal to the resistance between the red and blue wires, the motor will assume mid-position. When, however, the resistance between the red and white wires is increased, and the resistance between the red and blue wires is decreased, the motor will move in one direction to a new position. Similarly, when the resistance between the red and blue wires is increased and the resistance between the red and white wires is decreased, the motor will move in the opposite direction to a new position.

As shown, the red terminal of the motor 152 is connected by a wire 221 to the control arm 211 of the limit controller 210. The white terminal of the motor 152 is connected by wires 222, 223 and 224 to the left-hand ends of the control resistances 213 and 163. The blue terminal of the motor is connected by a wire 225 to the right-hand end of control resistance 163, while the control arm 162 is connected by a wire 226 to the right-hand end of control resistance 213.

Under normal operation, the predetermined difference in temperature between the return air and discharge air will exist, this causing the control arm 211 to engage the extreme right-hand end of control resistance 213. This causes the control arm 162 of the humidity controller 50 to be connected to the red terminal of the motor 152 as follows: wire 221, control arm 211, right-hand end of control resistance 213, and wire 226 to control arm 162. At this time, it will be noted, the control resistance 213 is connected between the red and white terminals of the motor 152 by wires 221, 223 and 222. To balance out the effect of this resistance on the motor relay, a resistance 227 is connected between wires 226 and 225. This resistance is equal in value to the resistance 213 and is connected between the red and blue terminals of the motor as follows: red terminal of motor, wire 221, control arm 211, wire 226, resistance 227 and wire 225 to the blue terminal of the motor. By this arrangement, it will be apparent that when the predetermined difference in temperature exists between the return air and the discharge air, the controller 210 will place the humidity controller in full control of the proportioning motor 152 for controlling the supply of heating fluid to the reheat 19.

If now should too much heat be supplied to the reheat 19 by the humidity controller 18, the discharge air temperature will rise to such a value that the difference in temperature be-

tween the return and discharge air falls below the predetermined value. This will cause the control arm 211 to be shifted towards the left across control resistance 213, this decreasing the portion of said resistance which is connected between the red and white terminals of the motor and increasing the portion of said resistance which is connected between the red and blue terminals of the motor. This, in a manner which should now be apparent, will cause movement of the motor 152 in a direction for reducing the supply of heated fluid to the reheat. The limit controller 210 therefore acts to prevent the reheat 15 from delivering too much heat to the air being conditioned, thereby preventing actual heating of the conditioned space and uneconomical operation of the system.

While I have shown a reheat limit controller which is responsive to the difference between the temperatures of the return and discharged air, it will be apparent that if desired, the limit controller may be made responsive to space temperature, and arranged to prevent operation of the reheat when the space temperature is excessive.

From the foregoing description, it should be apparent that I have provided an air conditioning system which is especially adapted for internal combustion engine drive, such system acting to automatically maintain proper temperature and humidity conditions within the conditioned space, and further providing for recovery of the heat dissipated by the system and for automatically dissipating only such portion of such recovered heat as is not necessary for other uses.

While my invention relates to air conditioning systems utilizing internal combustion engines, it will be apparent that certain features are of broader application, having utility apart from air conditioning or apart from internal combustion engine control. It will also be apparent that many changes which are within the scope of my invention will be apparent to those skilled in the art. I, therefore, desire to be limited only by the scope of the appended claims and the prior art.

I claim as my invention:

1. In a system of the class described, in combination, a cooling device, means for supplying a cooling medium to said cooling device including a compressor, means for gradually varying the output of said compressor, control means influenced by the temperature of said cooling device for controlling said varying means to vary compressor output for maintaining the temperature of the cooling device substantially constant, means responsive to a cooling load affecting condition for adjusting said control means for determining the cooling action maintained thereby, and means actuated with said compressor output varying means and arranged to place said compressor out of operation when said varying means reduces the operation of said compressor to a predetermined minimum value.

2. In a refrigeration system, in combination, an evaporator, means for supplying refrigerant to said evaporator, a compressor for reducing the pressure in said evaporator, a controller for varying the output of said compressor, a device responsive to the pressure in said evaporator for positioning said controller to cause a constant pressure to be maintained within said evaporator, means responsive to a condition affecting the refrigeration load for adjusting said pressure re-

5 sponsive device to cause the pressure maintained by said device to be varied in accordance with said condition, and means actuated with said controller and arranged to place said compressor out of operation when its output is reduced to a predetermined low value.

3. In an air conditioning system, in combination, a cooling device, means for passing air in heat exchange relationship with said cooling device and to a space to be conditioned, means for supplying a cooling medium to said cooling device including an internal combustion engine, a controller for varying the output of said internal combustion engine, control means influenced by the temperature of said cooling device for controlling said controller to vary the engine output in a manner to maintain the cooling device at constant temperature, and means responsive to a cooling load affecting condition of the air in the space being conditioned for adjusting said control means to thereby cause the cooling effect of the cooling device to be varied in accordance with said condition.

4. In an air conditioning system, in combination, a cooling device, means for passing air in heat exchange relationship with said cooling device and to a space to be conditioned, means for supplying a cooling medium to said cooling device including a compressor, a controller for varying the output of said compressor, control means influenced by the temperature of said cooling device for causing actuation of said controller to maintain the cooling device at constant temperature, means responsive to a cooling load 25 affecting condition of the air in the space being conditioned for adjusting said control means to thereby cause the cooling effect of the cooling device to be varied in accordance with said condition, and means actuated by said control means with said controller for terminating operation of said compressor when said controller reduces the compressor output to a predetermined value.

5. In a system of the class described, a refrigeration system having a condenser and a compressor, an internal combustion engine for driving said compressor, heat exchange means for recovering waste heat from said internal combustion engine, heat utilizing means, means for passing heat exchange fluid through said condenser, said waste heat recovering means, and said heat utilizing means, means for passing heat exchange fluid from said utilizing means to said condenser including a heat dissipating means, by-pass means for said fluid around said heat dissipating means, and automatically controlled valve means for varying the proportions of said fluid passed through said heat dissipating means and said by-pass.

6. In a system of the class described, a refrigeration system having a condenser and a compressor, an internal combustion engine for driving said compressor, heat exchange means for recovering waste heat from said internal combustion engine, heat utilizing means, means for passing heat exchange fluid first through said condenser, then through said waste heat recovering means and then through said heat utilizing means, means for passing heat exchange fluid from said utilizing means to said condenser including a heat dissipating means, by-pass means for said fluid around said heat dissipating means, valve means for varying the proportions of the fluid passed through said heat dissipating means and said by-pass means, and means responsive

to the temperature of the heat exchange fluid entering the condenser for controlling said valve means.

7. In a system of the class described, a refrigeration system having a condenser and a compressor, an internal combustion engine for driving said compressor, heat exchange means for recovering waste heat from said internal combustion engine, heat utilizing means, means for passing heat exchange fluid through said condenser to said heat utilizing means, by-pass means around said heat utilizing means, valve means associated with said by-pass means for varying the proportions of the heating fluid passed through said heat utilizing means and said by-pass means, means for passing heat exchange fluid from said utilizing means to said condenser including a heat dissipating means, by-pass means for said fluid around said heat dissipating means, and automatically controlled valve means for varying the proportions of said fluid passed through said heat dissipating means and said last mentioned by-pass means for controlling the heat content of the fluid being supplied to said condenser.

8. In a system of the class described, a refrigeration system having a condenser and a compressor, an internal combustion engine for driving said compressor, heat exchange means for recovering waste heat from said internal combustion engine, heat utilizing means, means for passing heat exchange fluid through said heat exchange means to said heat utilizing means, means for passing heat exchange fluid from said utilizing means to said condenser including a heat dissipating means, by-pass means for said fluid around said heat dissipating means, and automatically controlled valve means for varying the proportions of said fluid passed through said heat dissipating means and said last mentioned by-pass means for controlling the heat content of the fluid being supplied to said condenser.

9. In a system of the class described, a refrigeration system having a condenser and a compressor, an internal combustion engine for driving said compressor, heat exchange means for recovering waste heat from said internal combustion engine, heat utilizing means, means for passing heat exchange fluid through said heat exchange means to said heat utilizing means, means for passing heat exchange fluid from said utilizing means to said condenser, valve means for adding cool heat exchange fluid to said heat exchange fluid passing to said condenser, and means for controlling said valve means in a manner to prevent the temperature of the heat exchange fluid being delivered to the condenser from exceeding a predetermined value.

10. In an air conditioning system, in combination, a conditioning chamber through which air delivered to a space is adapted to be passed for a conditioning action, a cooling device in said conditioning chamber, means including a device responsive to the temperature of the space in control of said cooling device, by-pass means around said cooling device, damper means for controlling the proportions of the air passed through said cooling device and said by-pass, a reheating device for reheating the air, and moisture responsive means for sequentially controlling said damper means and said reheating device.

11. In an air conditioning system, in combination, a conditioning chamber, means for causing flow through said chamber of air to be

conditioned, a cooling and dehumidifying device in said chamber, a reheating device in said chamber, temperature responsive means for controlling said cooling and dehumidifying device, humidity responsive means for controlling said reheating device to reheat the air cooled by said cooling and dehumidifying device, and means responsive to the difference in temperature between the air entering said chamber and leaving said chamber for additionally controlling said reheating device to reduce the amount of reheating, irrespective of the action of said humidity responsive means, if such temperature differential becomes too great as a result of operation of the reheating device by said humidity responsive means.

12. In a system of the class described, a refrigeration system including an evaporator and a compressor, an internal combustion engine for driving said compressor, a speed controller for varying the speed of said engine, control means influenced by the temperature of the evaporator for gradually adjusting said speed controller in a manner to maintain the evaporator temperature substantially constant, means responsive to a condition affecting the load on the system for adjusting said control means to thereby vary the evaporator temperature maintained in accordance with variations in said condition, and means actuated by said control means with said speed controller for starting and stopping said engine, said last mentioned means being arranged to cause starting of the engine when the speed controller is adjusted for a predetermined minimum speed and for causing stopping of the engine when the speed controller is adjusted to cause engine operation below said predetermined minimum.

13. In a system of the class described, a refrigeration system including an evaporator and a compressor, an internal combustion engine for driving said compressor, a speed controller for varying the speed of said engine, control means influenced by the temperature of the evaporator for gradually adjusting said speed controller in a manner to maintain the evaporator temperature substantially constant, means responsive to a condition affecting the load on the system for adjusting said control means to thereby vary the evaporator temperature maintained in accordance with variations in said condition, and means actuated by said control means with said speed controller for starting said engine when said speed controller is adjusted to obtain an engine speed above a predetermined value.

14. In a system of the class described, a refrigeration system including an evaporator and a compressor, an internal combustion engine for driving said compressor, a speed controller for varying the speed of said engine, control means influenced by the temperature of the evaporator for gradually adjusting said speed controller in a manner to maintain the evaporator temperature substantially constant, means responsive to a condition affecting the load on the system for adjusting said control means to thereby vary the evaporator temperature maintained in accordance with variations in said condition, and means actuated by said control means with said speed controller for stopping said engine when said speed controller is adjusted to reduce the engine speed below a predetermined value.

15. In a system of the class described, a cooling device, means for passing air in heat exchange relationship with said cooling device and to a

space to be conditioned, means for supplying cooling medium to said cooling device including a compressor, said compressor having an inlet and an outlet, a by-pass connecting said inlet and outlet, an unloader valve in said by-pass for unloading said compressor, an internal combustion engine for driving said compressor, said engine having a speed controller and a starting motor, control means influenced by the cooling effect of the cooling device for gradually adjusting said speed controller, means responsive to a condition affecting the load on the system for adjusting said control means to thereby vary the cooling effect of the system in accordance with variations in said condition, means actuated by said control means with said speed controller for energizing said starting motor when the speed controller is adjusted to demand an engine output above a predetermined minimum, and means for causing said unloader valve to be open when said starting motor is in operation.

16. In a system of the class described, a cooling device, means for passing air in heat exchange relationship with said cooling device and to a space to be conditioned, means for supplying cooling medium to said cooling device including a compressor, said compressor having an inlet and an outlet, a by-pass connecting said inlet and outlet, an unloader valve in said by-pass for unloading said compressor, an internal combustion engine for driving said compressor, said engine having a speed controller and a starting motor, control means responsive to the demand for refrigeration in said space for gradually adjusting the speed controller in accordance with such demand, means actuated by said control means with said speed controller for energizing said starting motor when the speed controller is adjusted to demand an engine output above a predetermined minimum, and means for causing said unloader valve to be open when said starting motor is in operation while closing said unloader valve after the engine is in operation.

17. In a system of the class described, a cooling device, means for passing air in heat exchange relationship with said cooling device and to a space to be conditioned, means for supplying cooling medium to said cooling device including a compressor, said compressor having an inlet and an outlet, a by-pass connecting said inlet and outlet, an unloader valve in said by-pass for unloading said compressor, an internal combustion engine for driving said compressor, said engine having a speed controller and a starting motor, control means influenced by the cooling effect of the cooling device for gradually adjusting said speed controller, means responsive to a condition affecting the load on the system for adjusting said control means to thereby vary the cooling effect of the system in accordance with variations in said condition, means for energizing said starting motor upon demand for refrigeration in said space, and means for causing said unloader valve to be open when said starting motor is in operation while closing said unloader valve after the engine is in operation.

18. In a system of the class described, a cooling device, means for passing air in heat exchange relationship with said cooling device and to a space to be conditioned, means for supplying cooling medium to said cooling device including a compressor, said compressor having an inlet and an outlet, a by-pass connecting said inlet and outlet, an unloader valve in said by-pass for unloading said compressor, electromagnetic

means adapted when energized to open said unloader valve, an internal combustion engine for driving said compressor, said engine having a speed controller and a starting motor, control means responsive to the demand for refrigeration in said space for gradually adjusting said speed controller in accordance with such demand, switching means actuated by said control means with said speed controller for energizing said starting motor and said electromagnetic means when the speed controller is adjusted to demand an engine output above a predetermined minimum, and means for deenergizing said starting motor and said electromagnetic means after said engine is in operation.

19. In a system of the class described, a cooling device, means for passing air in heat exchange relationship with said cooling device and to a space to be conditioned, means for supplying cooling medium to said cooling device including a compressor, said compressor having an inlet and an outlet, a by-pass connecting said inlet and outlet, an unloader valve in said by-pass for unloading said compressor, electromagnetic means adapted when energized to open said unloader valve, an internal combustion engine for driving said compressor, said engine having a starting motor, switching means responsive to a demand for refrigeration in said space for energizing said electromagnetic means and said starting motor, and means actuated in response to operation of the engine for deenergizing said starting motor and said electromagnetic means after said engine is in operation.

20. In a system of the class described, in combination, a conditioning chamber through which air is passed to a conditioned space, a cooling device in said chamber, a by-pass for air around said cooling device, damper means for controlling the proportions of the air flowing through said cooling device and by-pass, means for supplying cooling medium to said cooling device including a compressor, an internal combustion engine for driving said compressor, said engine having a starting motor and a speed controller, control means influenced by the temperature of the cooling device for adjusting said speed controller for maintaining the cooling device at constant temperature, means responsive to the temperature of the space for adjusting said control means in a manner to decrease the temperature of said cooling device upon rise in space temperature, switching means actuated by said control means for energizing said starting motor when said controller is adjusted to demand an engine output above a predetermined value, and means responsive to the humidity in said space for controlling said damper means.

21. In a system of the class described, in combination, a conditioning chamber through which air is passed to a conditioned space, a cooling device in said chamber, a by-pass for air around said cooling device, damper means for controlling the proportions of the air flowing through said cooling device and by-pass, means for supplying cooling medium to said cooling device including a compressor, an internal combustion engine for driving said compressor, said engine having a starting motor and a speed controller, control means influenced by the temperature of the cooling device for adjusting said speed controller for maintaining the cooling device at constant temperature, means responsive to the temperature of the space for adjusting said control means in a manner to decrease the temperature of said cool-

ing device upon rise in space temperature, switching means actuated by said control means for energizing said starting motor when said controller is adjusted to demand an engine output above a predetermined value, a re heater for re-heating air cooled by said cooling device, means for delivering waste heat from the engine to said re heater, and means responsive to the humidity in said space for controlling said damper means and said re heater.

22. In an air conditioning system, in combination, a conditioning chamber through which air is passed to a conditioned space, a cooling device in said chamber, a by-pass for air around said cooling device, damper means for controlling the proportions of the air passed through said cooling device and said by-pass, means responsive to the humidity of the air in said space for gradually controlling said damper means in a manner to decrease the flow of air through said cooling device upon increase in humidity, means influenced by the temperature of the cooling device for maintaining said cooling device at constant temperature, and means responsive to the temperature in said space for adjusting said last mentioned means in a manner to lower the temperature of the cooling device upon rise in space temperature.

23. In an air conditioning system, in combination, a conditioning chamber through which air is passed to a conditioned space, a cooling device in said chamber, a by-pass for air around said cooling device, damper means for controlling the proportions of the air passed through said cooling device and said by-pass, means responsive to the humidity of the air in said space for gradually controlling said damper means in a manner to decrease the flow of air through said cooling device upon increase in humidity, and means responsive to the temperature of the air in said space for gradually lowering the temperature of said cooling device upon rise in space temperature.

24. In an air conditioning system, in combination, a conditioning chamber through which air is passed to a conditioned space, a cooling device in said chamber, a by-pass for air around said cooling device, damper means for controlling the proportions of the air passed through said cooling device and said by-pass, a re heater for heating the air cooled by said cooling device, means responsive to the humidity of the air in said space for controlling said damper means and said re heater in a manner to decrease the flow of air through said cooling device to a minimum upon rise in humidity to a predetermined value and then to place said re heater in operation upon

continued rise in humidity, and means responsive to the temperature of the air in said space for gradually lowering the temperature of said cooling device upon rise in temperature.

- 5 25. In an air conditioning system, in combination, a conditioning chamber through which air is passed to a conditioned space, a cooling device in said chamber, a by-pass for air around said cooling device, damper means for controlling the 10 proportions of the air passed through said cooling device and said by-pass, a re heater for heating the air cooled by said cooling device, and means responsive to the humidity of the air in said space for controlling said damper means and said 15 re heater in a manner to decrease the flow of air through said cooling device to a minimum upon rise in humidity to a predetermined value and then to place said re heater in operation upon continued rise in humidity.
- 20 26. The combination of a compressor, an internal combustion engine with an exhaust manifold, a cranking motor put in motion by a starter switch to start said engine, a by-pass from the low pressure to the high pressure side of the 25 compressor, an electrically operated valve controlling the by-pass, and means to open the said valve when the cranking motor is energized and to keep said valve open until the cranking motor is de-energized.
- 30 27. The combination of a compressor, an internal combustion engine with an exhaust manifold, a cranking motor to start said engine, a by-pass from the low pressure to the high pressure side of the compressor, an electrical valve 35 controlling the by-pass, means to open said valve when cranking motor is energized and until it is de-energized, irrespective of the temperature of the engine.
28. In an air conditioning system, in combination, a conditioning chamber, means for passing air to be conditioned through said chamber and to a space to be conditioned, a cooling and dehumidifying device in said chamber for cooling the air passing therethrough, means responsive 40 to the temperature of the air in the space being conditioned for operating said device when the space temperature becomes too high whereby the air is cooled, a re heater in said chamber, means responsive to the relative humidity of the air in 45 the space for operating said re heater to raise the temperature of the air upon increase in humidity, and other temperature responsive means in control of said re heater to reduce its heating effect, irrespective of the value of the relative 50 humidity, if such reheating causes the temperature of the air to be increased too much.
